UNITED STATES PATENT OFFICE

GARABED NAJARIAN, OF NEW HAVEN, CONNECTICUT

WIRE DRAWING MACHINE

Application filed May 13, 1930. Serial No. 451,905.

This invention relates to an improvement in wire-drawing machines and particularly to multi-draw machines for the production of wire.

The main object of this invention is to produce a simple, compact and reliable machine of the type referred to, constructed with particular reference to efficiency, and in which two or more draws may be effected without requiring manual rehandling of the wire.

With the above and other objects in view, as will appear from the following, my invention consists in a wire-drawing machine characterized by its provision with a pair of drawing-die passages of different diameters; of a first-draw pull-reel for drawing wire through the larger of the two said die-passages; a second-draw pull-reel for drawing wire through the smaller of the two said die-passages; an idler-reel interposed between the said first-draw pull-reel and the said second-draw pull-reel; and means for driving the two said pull-reels.

My invention further consists in a wire-drawing machine characterized as above and having certain other details of construction and combinations of parts as will be herein-after described and particularly recited in the claims.

In the accompanying drawing:

Fig. 1 is a view in side elevation of a wire-drawing machine embodying my invention;

Fig. 2 is a top or plan view thereof;

Fig. 3 is a vertical, transverse, sectional view thereof, taken on the line 3-3 of Fig. 2, but on a larger scale; and

Fig. 4 is a broken, detail, sectional view taken on the line 4-4 of Fig. 3.

In the embodiment of my invention herein chosen for illustration, I employ a first-draw pull-reel 10 secured to a vertical drive-shaft 11 by means of a key 12 and provided in its under-face with an annular ball-race 13 receiving a series of ball-bearings 14 also rolling in a complementary ball-race 15 formed in the upper-face of a bed-plate 16 supported upon a skeletonized-frame 17 having supporting-legs 18.

The reduced lower-end 19 of the vertical drive-shaft 11 is journaled in a boss 20 de-

pending from the under-face of the bed-plate 16 and is provided at its lower end with a worm-wheel 21 meshing into a worm 22 secured to the shaft 23 of an electric motor 24 or other suitable source of motive power.

The upper-face of the first draw pull-reel 10 is formed with an annular ball-race 25 receiving a series of ball-bearings 26 which also roll in a complementary ball-race 27 formed in the under-face of an idler-reel 28 having a central bearing-boss 29 turning freely upon the drive-shaft 11 by means of which it is centered.

The said idler-reel 28 is provided at its upper edge with an outwardly-projecting annular flange 30 having gear-teeth 31 cut in its periphery for meshing into a retarding-pinion 32 rotating upon the reduced upper-end 33 of a stud 34 upstanding from a boss 35 formed upon the upper-face of the bed-plate 16 near the edge thereof, as shown in Fig. 3 of the drawing.

The upper-face of the idler-reel 28 is formed with an annular ball-race 36 receiving a series of ball-bearings 37 which also bear in a race-way 38 formed in the under-face of a second-draw pull-reel 39.

The said second-draw pull-reel is coupled to the vertical driveshaft 11 near the upper-end thereof by means of a key 40 and is provided in the upper-face of its vertical flange 41 with a series of vertical pins 42 designed to increase the capacity of the said reel without unduly adding weight thereto.

In the operation of my improved drawing-machine, the wire 43 passes from a storage-reel, or other source of supply (not shown), through a passage 44 in a first-draw die-block 44^a, which serves to reduce the diameter thereof of one stage, and around the periphery of the first-draw pull-reel 10, from which the convolutions thereof gradually creep upward to the periphery of the intermediate or idler-reel 28, from where the wire—now reduced one stage by being drawn through the first-draw die-block 44^a—passes around an idler-roll 45, thence through a passage 46 in a second-draw die-block 46^a and around the periphery of the flange 41 of the second-draw pull-reel 39, which latter, being of larger diameter than 100

the first-draw pull-reel 10, will serve to keep an appropriate draft upon the wire which, after having passed through the second-draw die-block 46^a, is of smaller diameter but of 5 greater length than it was when wrapped around the first-stage pull-reel 10.

After a sufficient amount of wire has been wound upon the second-draw pull-reel 39, the machine may be stopped and the wire removed, preparatory to continuing the double-draw operation.

One of the major difficulties encountered in the multiple drawing of wire, and especially steel wire, has been that the wire becomes 15 brittle, with consequent repeated breakage. By passing the wire from the first-draw pull-reel 10 and over the idler-reel 28 before the wire is drawn through the second-draw die-block 46^a, ample opportunity is given the 20 wire to properly cool.

To assist in the cooling operation, I encircle the periphery of the idler-reel 28 with a ring-like air-tube 49 having a series of air-ports 50 formed in its inner-face and 25 directed upon the convolutions of the wire wrapped about the said idler-reel. The ring-like air-tube 49 is connected into the vertical reach 51 of an air-supply pipe 52, which carries at its upper end a segmental air-chamber 53 having its inner-face provided with air-ports 54 directed at the convolutions of wire located upon the periphery of the second-draw pull-reel 39.

To prevent the idler-reel 28 from rotating 35 too freely and thus permitting the convolutions of wire wound thereupon to loosen the snarl, I employ a friction-clamp 55 having a pair of complementary resilient arms 56—56 embracing the stud 34 before referred to and 40 frictionally clamped thereupon by means of a bolt 57. The inner end of the said friction-clamp 55 is provided with an upstanding coupling-pin 58 extending through the retarding-pinion 32 before referred to and acting 45 to restrain the rotation thereof and hence of the idler-reel 28.

It will be understood by those skilled in the art that my invention may assume varied physical forms without departing from my 50 inventive concept, and I, therefore, do not limit myself to the specific embodiment herein chosen for illustration, but only as indicated in the appended claims.

I claim:

55. 1. In a wire-drawing machine, the combination with a pair of drawing-die passages of different diameters; of a first-draw pull-reel for drawing wire through the larger of the two said die-passages; a second-draw 60 pull-reel arranged coaxially with said first-draw pull-reel for drawing wire through the smaller of the two said die-passages; an idler-reel concentric with and interposed between the said first-draw pull-reel and the 65 said second-draw pull-reel, the wire drawn

from the first-draw pull-reel being transferred to the idler-reel by slipping directly from the former to the latter, and feeding from said idler-reel to said smaller die-passage and thence to said second-draw pull-reel; and means for driving the two said pull-reels.

2. In a wire-drawing machine, the combination with a pair of drawing-die passages of different diameters; of a first-draw pull-reel for drawing wire through the larger of the two said die-passages; a second-draw pull-reel coaxially mounted with respect to and larger in diameter than the said first-draw pull-reel for drawing wire through the smaller of the two said die-passages; an idler-reel coaxial with and interposed between the said first-draw reel and the said second-draw reel, the wire drawn from the first-draw pull-reel being transferred to the idler-reel by slipping directly from the former to the latter, and feeding from said idler-reel to said smaller die-passage and thence to said second-draw pull-reel and means for driving the two said pull-reels.

3. In a wire-drawing machine, the combination with a pair of drawing-die passages of different diameters; of a drive-shaft; a first-draw pull-reel mounted upon and coupled to the said drive-shaft for pulling wire through the larger of the two said die-passages; a second-draw pull-reel also mounted upon and coupled to the said drive-shaft for drawing wire through the smaller of the two said die-passages; and an idler-reel interposed between the two said pull-reels and mounted upon the said drive-shaft with capacity for rotation independent thereof, the wire drawn from the first-draw pull-reel being transferred to the idler-reel by slipping directly from the former to the latter, and feeding from said idler-reel to said smaller die-passage and thence to said second-draw pull-reel.

4. In a wire-drawing machine, the combination with a pair of drawing-die passages of different diameters; of a first-draw pull-reel for drawing wire through the larger of the two said die-passages; a second-draw pull-reel arranged coaxially with said first-draw pull-reel for drawing wire through the smaller of the two said die-passages; an idler-reel coaxial with and interposed between the said first-draw pull-reel and the said second-draw pull-reel and partly nested within one thereof, the wire drawn from the first-draw pull-reel being transferred to the idler-reel by slipping directly from the former to the latter, and feeding from said idler-reel to said smaller die-passage and thence to said second-draw pull-reel; and means for driving the two said pull-reels.

5. In a wire-drawing machine, the combination with a pair of drawing-die passages of different diameters; of a first-draw pull-reel for drawing wire through the larger of

the two said die-passages; a second-draw pull-reel arranged coaxially with said first-draw pull-reel for drawing wire through the smaller of the two said die-passages; an idler-reel coaxial with and interposed between the said first-draw pull-reel and the said second-draw pull-reel and partly nested within one thereof, the wire drawn from the first-draw pull-reel being transferred to the idler-reel by slipping directly from the former to the latter, and feeding from said idler-reel to said smaller die passage and thence to said second-draw pull-reel; means for retarding rotation of said idler-reel; and means for driving the two said pull-reels.

6. In a wire-drawing machine, the combination with a pair of drawing-die passages of different diameters; of a first-draw pull-reel for drawing wire through the larger of the two said die-passages; a second-draw pull-reel arranged coaxially with said first-draw pull-reel for drawing wire through the smaller of the two said die-passages; an idler-reel coaxial with and interposed between the said first-draw pull-reel and the said second-draw pull-reel and partly nested within one thereof, the wire drawn from the first-draw pull-reel being transferred to the idler-reel by slipping directly from the former to the latter, and feeding from said idler-reel to said smaller die-passage and thence to said second-draw pull-reel; means for retarding rotation of said idler-reel including a member driven by said idler-reel and a friction brake device applied to said member; and means for driving the two said pull-reels.

In testimony whereof, I have signed this specification.

GARABED NAJARIAN.
